UNITED STATES PATENT OFFICE.

WILLIAM D. MCNAULL, OF TOLEDO, OHIO.

STEAM-BOILER.

SPECIFICATION forming part of Letters Patent No. 684,585, dated October 15, 1901.

Application filed January 23, 1901. Serial No. 44,446. (No model.)

To all whom it may concern:

Be it known that I, WILLIAM D. MCNAULL, residing at Toledo, in the county of Lucas and State of Ohio, have invented certain new and useful Improvements in Steam-Boilers, of which the following is a specification, reference being had therein to the accompanying drawings.

This invention relates to water-tube boilers of the character in which two "headers," as they are called, receive the ends of the water-tubes and are themselves connected to a cylindrical drum or drums, so that circulation may be maintained through the cylindrical drum, the headers, and the water-tubes.

The object of the invention is to improve the construction of the headers, so that tubes can be easily removed and replaced and so as to cheapen the construction of headers and improve them in the matter of strength; also, to improve the hand-hole stoppers for the removal of tubes and to improve the connection of the headers to the cylinders or drums of the boiler.

Figure 1 is a side elevation of a boiler in place, showing the general arrangement of parts, the setting being in section. Fig. 2 is a front elevation and partial section of a boiler consisting of two drums or shells mounted on one header. Fig. 3 is an edge view of one of the headers. Fig. 4 is a cross-section, enlarged, of the channel-bar or header-box edge with sections of face-plates riveted thereto, showing a cross-section of one of the face-caps and hand-plates which cover the holes in the faces of the headers. Fig. 5 is an elevation of part of one of the baffle-plates. Fig. 6 is a face view of a hand-plate.

The numeral 1 indicates the cylindrical shell or drum of the boiler, which is usually supported on brickwork in whole or in part.

2 3 denote the front and rear headers, which are connected by the water-tubes 4. The headers or header-boxes 2 3 are alike and are each composed of flat front and rear plates a a. The a or outer plate of each header is perforated with a number of holes 5, equal in number to the water-tubes. The holes 5 are opposite the water-tubes and are a little larger than the tubes 4, so that the tubes 4 may enter the holes 5 in the header-plate a, thence passed through hole 6 in plate b, and

when the tube ends are in the holes 6 in each of the plates b the tube is there expanded and secured to both plates b of the two headers. 55 All the holes in the plates a a opposite the tubes will be covered by caps, as will be explained. The plates a b of the headers are flat plates cut to the desired form in outline, but remaining flat, so that there are no angles 60 in these plates to weaken the structure. The plates are held to rolled channel-bars 7 7, which bars are a common form of angle-iron and can be readily bent to form. The bar 7, (integral or spliced,) which constitutes the 65 edge piece of each header, is bent to the form desired to constitute the sides, top, and bottom of the header-box. The plates a b of the header are cut out in concave form at their upper edges, as at 12, and the channel-bars 7 7 are bent to follow the outline of this concavity, which is an arc conforming to cylinder 1. Then the flanges 8 8 of the channel-bar are riveted to the edges of the header-plates a b. Thus one head of each rivet in 75 the header is in the water which fills the header, and all the rivets are thus protected from exposure to excessive heat. The headers 2 3 are constructed for shipment by themselves, as are the drums or shells 1 and tubes 4. 80 The shells 1 are perforated near the ends where the headers are to be attached by holes extending radially through the shells. The concave portions of the bars 7 are also perforated on the same radial lines. When the shell 85 and headers are assembled, short tubes or thimbles 9 9 extend through the shell of the boiler and through the holes in bars 7. These short tubes or thimbles, extending radially with reference to shell 1, are expanded into 90 the holes in the channel-bar or edge bar of the headers and the holes in the cylinder-shell 1. The short tubes or thimbles thus brace each other, and as long as any two of these thimbles are in place the shell 1 and the header can only be separated forcibly by 95 shearing off one of the thimbles; but by removing the thimbles 9 in radial direction no more difficulty is found in replacing a thimble than with any other short expanded tube. 100 The headers I make usually about six inches between plates a b and the tubes 4 of four inches in diameter, although, of course, these sizes are not essential. The drum or shell 1

is reinforced by an external plate 10 at the line of perforations where the drum 1 is connected to the header, these reinforce-plates 10 being perforated, as are the shell-plates. It 5 is apparent that any convenient number of drums 1 may be connected by two headers. The form of header preferred for two drums is shown in Fig. 2. For a single drum the header will be made symmetrical, dotted lines 10 in connection with the full lines showing the slight change of form necessary for symmetry. The holes in plates *a* are slightly larger than the holes in plates *b*. The holes 14 in plates *a* are covered by hand-plates and caps, 15 as I will now explain. The hand-plates 15 are cast and have lugs or hooks 16 on their faces, between which lugs the body of a bolt 17 may pass. The bolt-head will not pass between such hooks, but must be put in from 20 the side. The cap-plate 18 is a round or saucer-like plate with a central perforation, through which the bolt 17 passes. A nut 19 on the outside of the cap serves to tighten the cap and hand-plate. When there is 25 steam-pressure inside the header, the hand-plates are held by such pressure, and with an ordinary gasket very tight joints can be made. The bolts do not pass through the hand-plates. Hence no bolt-packing is required. A tube 30 can be replaced at any time when the boiler is empty by removing the hand-plates and cap over the ends of such tube, cutting away the tube, and removing and replacing it through the outer holes. A tube-expander 35 passed through holes 14 serves to expand such tube in place. A baffle-plate 21 is preferably inserted between the tubes in rear of furnace 22 to deflect the fire downward before it passes up the uptake 23. This baffle-plate is made 40 in sections with the edges notched and may be passed in between the tubes flatwise and then turned on edge to act as a deflector. The boiler-setting is made to conform to the boiler, and no special claim of novelty is 45 made thereon. The drums 1 and tubes 4 are set up at the same inclination; but the water-line will of course be horizontal and will be preferably about on the line of the top of the boiler-setting, as shown at 25. The inclina-

tion of the boiler from the horizontal determines the rapidity of circulation of the water in large degree. I find that if the thimbles 9 equal in area about ten per cent. of the tubes 4 good results as to steadiness of circulation are obtained. The tendency of many water-tube boilers to foam is in great measure overcome by having the entry to the headers reduced in area. 50

What I claim is—

1. In a steam-boiler, the combination with 60 a cylindrical shell, arranged at an incline, and two similar header-boxes, each composed of flat plates and rolled channel-bars, the channel-bars embracing the edges of the header-plates and riveted thereto, the header-boxes being inclined and connected by water-tubes, and the header-boxes having concaves in which the shell rests, being secured to the shell by radial tubes expanded at their ends 65 inside the shell and header-boxes. 70

2. The combination, in a steam-boiler, of a cylindrical shell and two similar header-boxes, each box composed of flat plates and rolled channel-bars, the inner plates of the header-boxes being connected by water-tubes 75 expanded into holes in said plates, the outer plates having covered holes a little larger in diameter than said water-tubes and directly opposite thereto, so that tubes may be removed through said holes, substantially as 80 described. 85

3. The combination, in a steam-boiler, of a tubular cylindrical shell, similar water-boxes at each end of said shell composed each of two rolled plates and a channel-bar riveted 90 at the edges of said plates and conforming to concaves cut in the flat plates to fit to shell, and an interposed reinforce between the channel-bar and the shell, the bar, shell, and reinforce being held in place by thimbles expanded into openings radial to the shell, substantially as described. 95

In testimony whereof I affix my signature in presence of two witnesses.

WILLIAM D. MCNAULL.
